UNITARY PROPELLING HANDLE AND FILTER ASSEMBLY FOR SUCTION CLEANERS

John E. Vance, North Canton, Ohio, assignor to
The Hoover Company, North Canton, Ohio, a
corporation of Ohio

Application July 6, 1949, Serial No. 103,250

6 Claims. (Cl. 15—350)

1

This invention relates to suction cleaners and more particularly to the propelling handle and filter construction and the novel relationship of their component elements to one another.

Some of the principal objectives achieved by the present invention includes greater convenience, greater accessibility of the filter, reduction in the cost of manufacture, improved appearance, higher filter efficiency, and longer filter life. These and other advantages follow a rearrangement and simplification of parts as respects the propelling handle and the dirt filter together with its appurtenances. Another feature is the use of a pivoted motor-fan unit which pivots with the handle and the filter assembly. A quickly detachable appearance covering not only encloses the paper filter and its fittings but a major portion of the operating handle greatly improving the over-all appearance and concealing unsightly joints, fastenings, etc., thereby making it feasible to use parts with more economical surface finishes.

Accordingly, it is an object of the invention to provide a new and improved suction cleaner.

Another object is the provision of a new unitary propelling handle and filter assembly.

A further object is the provision of a novel filter assembly employing an inexpensive filter which is protected by the propelling handle and yet is easily and conveniently accessible for removal in any position of the handle.

Still another object is a suction cleaner handle and filter arrangement both of which are enclosed, at least in part, by a readily detachable appearance covering.

Another object is the provision of a suction cleaner in which a pivotable mounting supports both the propelling handle and the filter thereby obviating the need for a flexible connection between the filter and the body of the cleaner.

A still further object is the provision of a new and simple appearance covering for the filter and a new mode of detachably securing the same in place.

Another object of the invention is the provision of an improved filter adapter and a simple mode of removably attaching it to a suction cleaner.

Still another object is the provision of an improved mode of supporting a paper filter in place on a suction cleaner.

These and other objects will become apparent as consideration is given to the following specification taken in connection with the attached drawings in which:

Figure 1 is a perspective view of a suction

2

cleaner incorporating the invention in its various aspects;

Figure 2 is a vertical sectional view through the filter and propelling handle construction; and

Figure 3 is a sectional view along line 3—3 on Figure 2.

As indicated in Figure 1, the invention is shown as incorporated in a suction cleaner having a suction nozzle 10 communicating with upwardly and rearwardly extending, laterally spaced passageways 11 and 12. One passageway, as 11, may be utilized as a belt housing for the usual agitator journaled in the suction nozzle opening. The facing sides of passageways 11 and 12 are provided with airtight annular bearings for a semicylindrical housing 13 enclosing a motor-fan unit extending transversely of the cleaner parallel to the suction nozzle. The 10 motor-fan unit may be of any desired type well known in the art. Preferably, however, the fan eye communicates with the air passage 12 through the annular bearing at that end of the casing 13 in accordance with known practice. 20 The motor shaft extends into passage 11 and carries a belt pulley to drive the agitator.

The cleaner body is mounted upon a carriage 14 having upwardly extending brackets 15 journaled about the same bearing and pivot point as housing 13. Carriage 14 is provided with front 25 carrier wheels 16 and rear wheels 17.

As best illustrated in Figure 2, a tubular propelling handle is detachably secured to the lower rear corner of housing 13, as by screw 19. 30 The upper end of the handle is bent upwardly at 20 and then rearwardly in a plane parallel to the top side of housing 13. The outermost end of the handle is provided with the usual operating grip 21. Intermediate bend 20 and grip 21 35 is a mounting for an electric control switch 22 and the strain relief 23 for the service cord.

From the foregoing it will be clear that the propelling handle is rigidly secured to the lower, rear corner of the housing 13 for the pivotally 40 mounted motor-fan unit and that the housing rotates with the handle as the latter pivots in normal cleaning operation. It will also be observed that the space between the rear end of housing 13 and bend 20 in the handle provides a 45 large, protected and convenient space within which to mount the filter bag.

My novel arrangement of parts enables me to use a very simple, easily manufactured, low-cost paper filter bag 24. The cross-sectional contour 50 of this bag may be of any desired shape. How-

ever, as illustrated, a generally square shape is used conforming to the contour of the appearance covering and of housing 13. Thus, when inflated, it substantially occupies the entire cross-sectional area enclosed by the appearance bag.

The lower end of the filter is tailored to form a neck of reduced cross-section. The neck may be reinforced by a paper wrapping or otherwise and is designed to telescope over the outer end of a combined adapter tube and dirt trap 26. The outer end of tube 26, which is located within the filter, may carry a self-closing valve 27 of paper, rubber, plastic or other like material the non-operating position of which is that indicated in Figure 2. The rear portion of tube 26 and valve 27 prevent dirt and foreign material from falling back into the adapter and the cleaner body when the cleaner is not operating. When the cleaner is operating, however, the exhaust air pressure will force valve 27 to its extended open position allowing the dirt-laden air stream to pass through it freely. Dirt separated by the filter falls downwardly about the exterior of tube 26 where it remains trapped until the filter is removed from the adapter tube and the bag is emptied.

The lower end of tube 26 carries radially extending flange 28. The lower side of this flange fits behind retaining tabs 29-29 which hold the adapter tube 26 firmly seated in register with the fan exhaust passageway 30 located in housing 13. The top side of flange 28 is adapted to be detachably held in place by a single self-locking, spring biased latch 31 mounted on housing 13. The latch is provided with an operating lug 32 conveniently located for manual operation either by hand or by foot pressure to release the adapter tube and permit its easy removal from or replacement on the cleaner.

In order to hold the filter securely in place on tube 26 in an airtight manner it is preferred to use a spring clamping ring 33. Clamping ring spring 33 is held tightly compressed against the filter neck to lock it in place on tube 26 by means of a snap-acting toggle clamp 35 pivotally supported at 36 on the adapter tube. Clamp 35 and spring 33 open to release the filter neck when the thumb piece of clamp 35 is pivoted upwardly away from the tube.

The top of the filter bag is folded over and held closed by means of a clamping device such as spring clamp 37 which is held closed when its operating handle 38 is in the position shown in Figure 2. Pivoting handle 38 upwardly allows clamp 37 to expand so that it may be removed from the filter. A light tension spring 39 extends between the clamp and a hook 40 secured to the bent portion 20 of the operating handle to maintain the walls of the filter taut. It will thus be clear that the lower end of the bag is supported rigidly with the handle and housing 13 by means of the adapter fitting 26 while its upper end is resiliently connected to the cleaner handle by spring 39 and hook 40. Since the handle pivots with housing 13, it will be evident that no flexing of the filter ever occurs as a result of movement of the cleaner handle in cleaning a carpet.

To further protect the filter as well as to conceal it along with adjacent portions of the operating handle and the adapter fitting, use is made of an appearance covering generally indicated at 41. This covering may be of cloth, perforated plastic material or any other flexible porous material presenting a neat external appearance. The cover is so designed that it may be very easily

and readily secured in place or detached to permit convenient access and removal of the filter. As shown, this is accomplished by a plurality of snap fasteners 42, a pair of which are shown as located at the bottom of the covering and another pair at the top of the handle 18. The vertical edge of the covering perfectly overlies the upper, mid-portion of filter 24 although the opening edge may be located at an upper corner or to one side of the filter. A hook 43 on the lower edge of the opening interlocks with a hook on housing 13 while a similar spring biased hook 44 serves to secure the upper corner to the cleaner handle. As shown, the vertical edge of the bag is stiffened by a full length rod running from hook 43 to hook 44. This rod may be omitted if desired. The spring bias operates to place both hook 43 and hook 44 under tension thereby insuring that the hooks will remain firmly in place during use of the cleaner.

As will be noted from Figure 2, the appearance bag closes not only the filter but the entire mid-portion of the cleaner handle. For this reason it is unnecessary to place an expensive surface finish on the enclosed portion of the handle nor on any of the other parts located within the appearance covering.

Housing 13 provides a suitable form for both supporting and shaping the lower end of the appearance covering. A forming wire 45 is supported by the upper end of the handle at a point beneath the appearance covering and is shaped to underlie and support the upper end of the appearance covering so that its cross-sectional contour will also conform to that of its lower end, or to any other pleasing shape.

Operation

The operation of the invention will be self-evident from the foregoing description. When assembled as shown in Figures 1 and 2, the cleaner may be operated to clean a floor covering in the usual manner. The air stream passes up through the nozzle, through passage 12 and the hollow pivot bearing for the handle and motor-fan unit, through exhaust passageway 30, adapter tube 26, valve 27, and into filter bag 24. The separated dirt falls about the exterior of adapter tube 26 and is thereby effectively trapped against return to the fan chamber. Throughout the cleaning operation the filter 24 moves with the propelling handle without flexing or without any change in the uniform tension maintained on its walls by spring 39.

When it becomes necessary to empty the filter, it is merely necessary to unfasten hook 44 located on the upper top side of the handle at a point adjacent the grip. Hook 43 automatically unlatches, allowing the appearance cover to be unfolded to the under side of the handle. Spring 39 can then be unhooked from hook 40 as the operator's foot presses latch 31 releasing the adapter together with the filter from the cleaner. The filter may then be taken to a place of dirt disposal and cleaned by removing clamp 37 from the top of the bag.

Reassembly of the filter is extremely simple, it merely being necessary to fit the lower side of flange 28 of the adapter tube behind hooks 29-29 and snap the top of the adapter over latch 31. Spring 39 is then replaced as the appearance cover is folded back in place and hooks 43 and 44 re-engaged.

From the foregoing, it will be manifest that the present invention provides a suction cleaner

which is unusually simple in construction and operation. Not only does the arrangement present a new and unusual appearance, but the quickly detachable appearance covering is utilized in a unique manner to conceal the filter and its appurtenances as well as a major portion of the operating handle. Furthermore the appearance covering opens readily and quickly exposing all operating parts of the filter for convenient removal from the top side of the cleaner. Furthermore the arrangement is such that it is unimportant whether the handle is in its horizontal, inclined or vertical position as respects the accessibility and convenience of detaching or replacing the filter.

While I have shown and described but a single modification of my invention, it is to be understood that this modification is to be taken as illustrative only and not in a limiting sense. I do not wish to be limited to the particular structures shown and described, but to include all equivalent variations thereof except as limited by the scope of the claims.

I claim:

1. The combination with a suction cleaner having a wheel supported main body, a suction nozzle across the forward end of said body, a motor driven suction fan on said body rearwardly of said nozzle, conduit means for conducting air from said nozzle to the inlet of said fan, an exhaust air conduit for said fan, a filter adapter assembly mounted over the end of said exhaust air conduit, a tubular propelling handle rigidly supported on said exhaust air conduit and extending rearwardly therefrom in a plane spaced below said filter adapter, means for detachably securing the inlet of a paper filter over the discharge end of said filter adapter, a flexible appearance envelope enclosing said paper filter and the lower end of said handle from a point below the upper end of said paper filter, means for securing the upper end of said envelope about said handle and the lower end of the envelope about said filter adapter and said handle, and means for releasably closing said appearance envelope whereby the same may be opened to expose said paper filter and filter adapter from above for convenience in replacing a filter on said adapter without interference from said handle and said envelope.

2. The combination defined in claim 1 wherein the upper end of said tubular handle is curved upwardly and rearwardly to a hand grip portion lying in the same general plane as the upper side of said filter adapter, and wherein the upper end of said appearance envelope is secured to said handle adjacent said curved portion thereof so that the lower end of said handle and at least a major part of said curved portion thereof is normally enclosed by said appearance envelope.

3. The combination with a suction cleaner having a wheel supported body provided with a suction nozzle extending across the forward end thereof, a motor driven suction fan mounted on said cleaner body, an exhaust air conduit having a discharge end projecting rearwardly from said body and in communication with the discharge side of said suction fan, suction air conduit means leading from said nozzle to the inlet of said suction fan, said suction conduit, said suction fan and said exhaust conduit cooperating to provide a continuous dirty air passageway and including a swivel connection constructed and arranged to permit the discharge end of said exhaust conduit to pivot in a vertical plane rela-

tive to said cleaner body, a filter adapter for a paper filter mounted across the discharge end of said exhaust conduit, a tubular cleaner propelling handle rigidly secured to said exhaust conduit and extending rearwardly therefrom in a plane underlying said adapter, manually operable means for releasably securing a paper filter bag to said adapter, an appearance envelope enclosing the lower end of said handle and said filter adapter and forming an enclosure for said paper filter bag, means for securing the upper end of said envelope about said handle at a point above the top end of said paper filter, means for securing the lower end of said envelope about said exhaust conduit and the lower end of said handle, said envelope having a normally closed opening extending longitudinally thereof and positioned when opened to expose said filter and filter adapter from the sides thereof opposite said handle.

4. The combination with a suction cleaner having a wheel supported body, a tubular propelling handle pivotally connected to said cleaner, an air discharge conduit rigidly secured to said handle adjacent the lower end thereof so as to pivot with said handle, the discharge end of said conduit being located above said handle in closely spaced relation thereto and being adapted to receive and seat the inlet of a paper filter bag thereover, clamping means for releasably clamping a filter inlet to said conduit in an air tight manner, flexible covering means forming an appearance envelope for enclosing said filter bag and the lower end of said handle, means for securing the lower end of said envelope to said discharge conduit below said filter inlet and the clamping means therefor, means for securing the upper end of said envelope about said handle at a point above the top end of said filter, reinforcing and shaping means cooperating with the upper end of said envelope and with said handle to hold the walls of the upper end of said envelope in a predetermined shape to provide an enclosure for said filter bag, said envelope having an opening extending longitudinally thereof, the securing means for at least one end of said envelope being readily releasable to expose said filter and the clamping means therefrom from the side thereof opposite said handle whereby, when said handle is in an inclined position, opening of said envelope permits said filter to be readily removed and replaced from a position overlying said handle and without interference therefrom and whereby, when said envelope is closed, both said filter and the major portion of said handle are concealed from view.

5. The combination with a suction cleaner having a wheel supported main body, of a unitary propelling handle and power unit assembly pivotally connected to said body for pivotal movement with respect thereto about a horizontal axis extending transversely of said body, a motor driven suction fan within the lower end of said assembly operating about the aforesaid horizontal axis and having an inlet opening surrounding said axis, an air exhaust conduit projecting rearwardly from said fan, a tubular propelling handle secured to the lower rear side of said conduit, the upper end of said handle being generally parallel to but offset vertically from the lower end thereof to provide an unobstructed space for a filter bag overlying the lower end of said handle, a filter adapter extending generally parallel to said handle and mounted over the end of said exhaust conduit, clamping means for se-

curing the inlet end of a paper filter upon said adapter, a flexible envelope surrounding the lower end of said handle and co-operating therewith and with said exhaust conduit to form an enclosure for said adapter and said filter bag, means for securing the upper end of said envelope about said handle at a point above the upper end of said filter, said envelope having an opening extending lengthwise thereof, and releasable means for securing the lower end of said envelope to said exhaust conduit whereby said envelope may be opened to expose said adapter and said filter from a point overlying said handle.

6. The combination defined in claim 5 wherein said filter adapter is readily detachable from said exhaust conduit, and means for normally locking said adapter in place on said exhaust conduit

including manually operable latch means circumferentially spaced from said handle so that the handle does not interfere with the operation thereof.

5 JOHN E. VANCE.
